UNITED STATES PATENT OFFICE.

JESSE OLIVER, OF MEMPHIS, TENNESSEE, ASSIGNOR TO THOMAS B. TURLEY
AND WEST J. CRAWFORD, TRUSTEES, OF SAME PLACE.

THERMO-ELECTRIC BATTERY.

SPECIFICATION forming part of Letters Patent No. 660,305, dated October 23, 1900.

Application filed February 8, 1900. Serial No. 4,548. (No model.)

To all whom it may concern:

Be it known that I, JESSE OLIVER, a citizen of the United States, residing at Memphis, in the county of Shelby and State of Tennessee, have invented certain new and useful improvements in Thermo-Electric Batteries; and I do hereby declare the following to be a full, clear, and exact description of the same, reference being had to the accompanying drawings, forming a part of this specification, and to the letters of reference marked thereon.

This invention relates to improvements in electric generators in which the current is generated by variations in the temperature of thermo-electric couples and usually by the action of heat from a burner upon one portion of such couples, while the other portion of such couples is left or kept comparatively cool.

20 The objects of the invention are to provide a simple and highly-efficient thermo-battery embodying materials and with the elements assembled in such relation to each other and to the battery as a whole as to give a higher efficiency than has heretofore been obtained with the expenditure of a given amount of fuel; and the invention consists, primarily, in the arrangement of the couples whereby self-induction is eliminated and the difference in 30 potential between the couples is greatly increased.

Further, the invention consists in a novel alloy constituting one of the elements of the couples and in a novel manner of uniting the positive and negative elements constituting the couples.

Referring to the accompanying drawings, Figure 1 is a vertical section through a thermo-electric battery composed of a few superposed rings embodying my present improvements. Figs. 2 and 3 are detail enlarged plan views looking at opposite sides of one of the rings. Fig. 4 is an enlarged transverse section through one of the rings. Fig. 5 is a 40 detail section through one of the couples taken horizontally to show the manner of uniting the ends of the positive and negative elements.

Like letters of reference in the several figures indicate the same parts.

The positive and negative elements of the

couples in my improved battery are formed one of an alloy and relatively large in cross-section and the other of a metal or an alloy which is relatively a better conductor than the other element of the couple and relatively small in cross-sectional area. The larger element or that before referred to as an alloy I shall designate herein as the "positive" element and the latter or relatively-smaller element as the "negative" element, although it will be understood that this is a matter of designation only, as under differing conditions the direction of the current through the battery may be different. The alloy or positive element in my battery is preferably composed of aluminium, antimony, and zinc, and the preferred proportions are, approximately, antimony, two parts; zinc, one part, by weight, and aluminium, two percent. These positive elements are, to secure the most economical results, preferably radially grouped around a center in annular or ring form, and each is preferably, therefore, made segmental in shape and with the smaller ends all projecting toward the center. These elements are designated by the letter A in the accompanying drawings, and the opposing or negative elements by the letter B. These negative elements, as shown, are made of a plurality of strands of iron or steel wire, which are united to the positive elements by having their ends cast directly in the ends of the adjacent positive elements. Thus in forming a ring the wire or negative elements are set up 85 in the mold with their ends b in position to have the positive elements cast about them. The body portions of the positive and negative elements are in different planes, and the resultant ring will therefore be, in effect, spirally arranged, and one side of each spiral or convolution will be formed by a negative and the opposite side by a positive element. This manner of forming the battery is in contradistinction to the usual zigzag arrangement 90 of the elements, wherein the positive and negative elements alternate in the same plane, and the object of the new arrangement, in addition to facilitating the manufacture, is to eliminate as far as possible self-induction, 95 which in a large measure reduces the efficiency of the battery. To still further pro-

vent the effect of induction between the positive and negative elements, I arrange a metallic (preferably magnetic) screen between them, such screen taking the form of a flat laminated iron or metal ring C, which lies between the positive and negative elements and is insulated from both by suitable refractory insulation—such, for instance, as sheets of asbestos or mica D, although other insulating material may be employed where found desirable or advantageous.

Each of the positive elements has interposed between it and the next element a sheet or body of insulation F, preferably also of asbestos or mica; but the smaller or negative elements being so widely separated may be simply covered by an insulating material—such, for instance, as the asbestos ring G, which will serve not only to insulate the elements, but will also answer as a spacer for distancing the adjacent rings. This spacer preferably occupies or covers only a portion of the negative elements nearest their inner ends, leaving the outer ends thereof exposed for the radiation of heat and which radiation may be heightened by the circulation of water or by the application of moisture, which by its evaporation will reduce the temperature at this point.

30 In the most complete and highly-efficient embodiment of the invention the smaller or negative elements are extended beyond the alloy elements, so as to receive a greater proportion of heat, this being best secured by forming inwardly-extending reverse bends or loops b' in the elements, which are adapted for direct contact with the air or heated products of combustion, while the alloy or positive elements have their inner ends protected 35 by an insulating ring I of refractory material, such as asbestos or the like. This ring of asbestos or insulating material I may also contain a shield in the form of a metal ring K, which will in a measure still further prevent 40 the effect of induction between the elements and also serve as a form about which the elements may be grouped in regular order.

Obviously any number of rings formed as above may be stacked one upon the other, as 45 is usual in this class of battery, and they may be coupled either in multiple or in series, as occasion demands, for which purpose the take-off wires extend out from the first and last elements of the ring into convenient position 50 for the application of suitable conductors leading either to the adjacent rings or to mains from which the current is carried to the point of utilization.

The practical development of the thermo- 60 battery herein described has demonstrated that the efficiency of the battery is greatly reduced unless there be a perfect electrical contact between the positive and negative elements, which electrical contact must not be varied by the temperature to which the battery is subjected, and I have found that this contact can best be secured, particularly in

connection with negative elements of iron or steel, by coating the ends of the latter with a soldering-alloy which will intimately combine with the alloy of the positive elements. I have found that an efficient solder for this purpose may be composed of bismuth, tin, lead, and aluminium, the preferred proportions being tin, two parts; bismuth and lead, 75 one part each, and aluminium one-fourth of one part. The ends of the negative elements are first thoroughly coated with this solder and the positive elements then cast about such ends, the ends themselves being bent so 80 as to extend transversely of the positive elements, as shown clearly in Fig. 5 of the drawings, to give greater contacting surface.

Obviously the size of the rings and couples employed is immaterial and may be varied in 85 accordance with the desired capacity of the battery or the available burner or heater; but I have found that when arranged as above described the battery is highly efficient and gives both very high voltage and amperage 90 results. Thus with a ring composed of thirty couples and five inches and a quarter in diameter and one-half inch in thickness a voltage of not less than one and eight-tenths volts and two amperes may be secured without using artificial means to cool the outer ends of the couples and with a simple small vapor-burner for heating their inner ends.

While I have described my battery with the elements arranged in annular or ring form 100 and with the heat applied at the center, yet it is obvious that many features of the invention are applicable to any of the ordinary arrangements of thermo-batteries, and in some instances it may be found desirable to apply 105 the heat at the outer ends while a cooling medium is circulated through the center, as has heretofore been proposed.

Having thus described my invention, what I claim as new, and desire to secure by Letters Patent, is—

1. A thermo-electric battery having the elements extending substantially radially and with the positive elements located in one plane and the negative elements in a different but substantially parallel plane, substantially as described.

2. A thermo-electric battery embodying couples of positive and negative elements and a metallic screen interposed between the elements, substantially as described.

3. A thermo-electric battery embodying couples of positive and negative elements and an insulated metallic screen arranged between the elements to overcome the effects of induction between the elements, substantially as described.

4. A thermo-electric battery having a series of positive elements located in one plane and a series of negative elements in a different and parallel plane and a metallic screen insulated from and located between the positive and negative elements, substantially as described.

5. A thermo-electric battery having a series

- of radially-arranged alloy elements of relatively large cross-sectional area and insulated from each other and a series of elements of opposite polarity therefrom one connecting each adjacent pair of alloy elements, all of the elements of one polarity being located in one plane and all of the elements of opposite polarity in a different plane, substantially as described.
10. A thermo-electric battery embodying a series of elements of relatively large cross-sectional area and a plurality of independent elements of opposite polarity therefrom connecting the adjacent elements first mentioned, the arrangement being such that the elements of large cross-sectional area are connected by a number of independently-acting elements of opposite polarity each serving in its individual capacity independently of the others and one of which might be severed without destroying the operativeness of the battery; substantially as described.
15. A thermo-electric battery embodying a series of elements of relatively large cross-sectional area and a plurality of parallel elements of opposite polarity therefrom each relatively small in cross-sectional area connecting the adjacent elements first mentioned, substantially as described.
20. 8. In a thermo-electric battery the combination

nation with a series of elements of relatively large cross-sectional area arranged in a single plane, of a series of elements of opposite polarity arranged in a different plane therefrom with their ends connected with the ends of the former and having bends or loops extending beyond the ends of the former, substantially as described.

9. A thermo-electric battery embodying a series of radially-arranged positive elements of relatively large cross-sectional area arranged in compact form and each insulated from the other, a series of negative elements of relatively small cross-sectional area also arranged radially but arranged in a plane above the positive elements and having a reverse loop extending inwardly beyond the ends of the positive elements, a laminated metallic screen interposed between the positive and negative elements and insulation between the screen and elements and over the inner ends of the positive elements, substantially as described.

10. In a thermo-electric battery an element composed of an alloy of antimony, zinc and aluminium; substantially as described.

JESSE OLIVER.
